CLOCK FACE

Marion K. Summers, W. Commerce St.,
Brownstown, Ind. 47220

Filed Mar. 6, 1968, Ser. No. 10,866

Term of patent 14 years

(Cl. D42—1)

FIG. 2

FIG. 1

FIG. 1 is a front elevational view of a clock face showing my new design; and

FIG. 2 is a top plan view thereof.

The essential features of my design reside substantially in the full line disclosure on the drawing.

I claim:

The ornamental design for a clock face, substantially as shown and described.
